CONCEALED HINGE

Michael J. Economides, Brooklyn, N. Y.

Application August 5, 1944, Serial No. 548,181

4 Claims. (Cl. 16—135)

The present invention relates to improvements in concealed hinges.

One of its objects is to provide a concealed hinge for use in automobiles, buses and other vehicles, as well as fixed structures such as houses, which may be made, in major part, of stamped and bent sheet metal.

A further object is to provide a hinge of the type described whose fixed and swinging hinge members may readily be disengaged from each other and just as readily be locked into cooperative engagement with one another.

Another object is the provision of a hinge of the type described which carries, internally thereof, a door check.

Still another object is the provision of a hinge of the type described which may be used on doors opening either to the right or to the left.

These and other objects are attained by mechanism illustrated in the accompanying drawing in which

Figure 1 is a top view of the device;

Figure 2 is a side view of the swinging member and a face view of the fixed member of the device;

Figure 3 is a section on the line 3—3 of Figure 1;

Figure 4 is a section on the line 4—4 of Figure 2;

Figure 5 is a fragmentary section on the line 5—5 of Figure 2;

Figure 6 is a plan view of a blank out of which is fashioned the housing of the fixed member;

Figure 7 is a plan view of the locking plate of the device; and

Figure 8 is a plan view of the reversible guide plate of said device.

The fixed member of the hinge comprises a housing 10, a guide and spacer plate 11 and a locking and spacer plate 12. The housing is formed of a single H shaped piece or blank of sheet metal 13 upon whose cross bar 14 are formed dove-tailing projections 15. When said blank is folded over on the dotted lines 16 shown in Figure 6, the housing is formed.

The housing is a box-like structure having three superimposed compartments. The upper of said compartments has a front wall 20, two side walls 21 and a floor 22. It has no rear wall and no ceiling. The middle compartment has a rear wall 23, two side walls formed of the dovetail units 15, a ceiling 22 (which serves also as the floor of the upper compartment) and a floor 24. It has no front wall. The lower compartment has a front wall 25, two side walls 26, and

5 a ceiling 24 (which also serves as the floor of the middle compartment). The lower compartment has no back wall and no floor. Each of said walls is rectangular in shape and each of said floors (ceilings) is square in shape. Said floors lie in parallel planes, said front walls lie in a common plane which is parallel to the plane of the rear wall, all of the side walls on the left side lie in a common plane, and all of the side walls on the right side lie in a common plane, parallel to the plane of the side walls on the left side.

10 The walls 20, 21, 25 and 26 are provided with apertures 27 through which screws (not shown) are inserted to affix said housing to the door 15 jamb 28. Spaced, inverted, keyhole-shaped apertures 29 are formed in said blank before it is bent as aforesaid, the circular portions 30 thereof being formed in the floor 22, the shank portions 31 extending in parallel lines through floor 22 and into front wall 20, the square or base portions 32 thereof, being formed in said front wall 20.

15 Formed in floor 24, in registration with circular portions 30, are circular apertures 33. Also formed in floor 24, concentrically with said apertures 33, but not with each other, are two identical arc-shaped slots 34 whose adjacent ends face forward and whose diverging ends face, respectively, the left and right side walls which the dovetail units 15 constitute. Formed in front 20 wall 20, midway between base portions 32, is a square depression 35 which in turn has formed in it an internally threaded aperture 36. The rear wall 23 has a pair of spaced, rectangular apertures 37 formed therein, spaced from the side edges thereof, and adjacent floor 24. Rear wall 23 also has a pair of rectangular notches 38 formed therein at the side edges thereof, adjacent ceiling 22.

25 Guide plate 11 is a square piece of sheet metal whose dimensions enable it to fit snugly into the center compartment of the housing, adjacent, and parallel to, floor 24. Said plate is provided at its rear edge, with two spaced rectangular projections 40 which correspond in size and location to rear 30 wall apertures 37.

35 Formed in guide plate 11, and opening at the front edge thereof, are two slots 41 and 42. Slot 41 lies parallel with the side edges of said guide plate, its longitudinal axis intersecting at right angles the axis of one of the two circular apertures 33. The width of slot 41 corresponds to the diameter of said apertures 33 and the inner, closed end of said slot is curved to form a half circle concentric with said aperture 33. Slot 42 is arc-shaped in part and straight in part. Its

straight portion lies parallel with slot 41. Its arc-shaped portion registers with, and corresponds in all other respects to, that arc-shaped slot 34 which lies adjacent the last mentioned aperture 33.

Affixed to one side of guide plate 11, adjacent its front edge, is a leaf spring 43. Said spring does not obstruct passage through either of slots 41 and 42.

Locking plate 12 is also a piece of sheet metal whose dimensions enable it to fit snugly into the center compartment of the housing, on a plane parallel with the planes of ceiling 22, floor 24 and guide plate 11. Locking plate 12 is provided, at its rear edge, with a pair of projections 50 which correspond in size and location to rear wall notches 38. At its front edge it is provided with an apertured projection 51 flanked by a pair of projections 52. Projections 51 and 52 when bent upward on the dotted line 53, correspond, respectively, in shape, size and location, to depression 35 and that portion of keyhole-shaped apertures 29 which is formed in front wall 20 of the housing. Aperture 54 formed in projection 51 registers with aperture 36 which is formed in depression 35.

A pair of spaced slots 55 are formed in said locking plate, said slots being parallel to each other and to the side edges of said plate, and opening at the rear edge of the plate. The longitudinal axes of said slots intersect, respectively, at right angles, the axes of circular apertures 33. The inner, closed ends of said slots form half circles which are concentric with said apertures 33.

The swinging member of the hinge comprises a U or box-shaped body or housing 60 which may be bent out of a rectangular piece of sheet metal. The width and height of the body correspond, ordinarily, to the width and height of the fixed member of the hinge. Apertures 61 are formed in said body to accommodate screws (not shown) for affixing to the door 62.

Extending outwardly from the yoke portion of said U shaped body, either affixed thereto or integral therewith, is a hook-shaped arm 63 which lies on a plane perpendicular to the planes of the yoke and arm members of said U shaped body. Said hook-shaped arm is of a thickness that enables it, together with guide plate 11 and locking plate 12, to fit into the middle compartment of the housing.

At the end of the hook portion proper of said hook-shaped arm, at a distance from the yoke portion greater than the length of slot 41, is affixed a pintle 64 whose axis is perpendicular to the plane of said hook-shaped arm. The pintle has a base portion 65 which projects below the hook-shaped arm, the diameter of said base portion corresponding to the diameter of aperture 30 and to the width of slot 41. Above the hook-shaped arm, the pintle has a stem portion 66 and above that, a head portion 67. The diameter of the stem corresponds to the width of slots 55 as well as to the width of the shank portion 31 of the keyhole-shaped apertures 29. The diameter of the head corresponds to the width of base portion 32 of the keyhole-shaped apertures 29.

Projecting downwardly from said hook-shaped arm is a small combination guide and check member 70, said check member being spaced from pintle 64 substantially the same distance therefrom in the direction away from said U shaped body, as separates the arc-shaped slots 34 from the circular apertures 33. The thickness of said

check member corresponds to the width of slots 34 and 42.

The hinge is installed as follows: A recess is provided in the door jamb to accommodate the middle compartment of the fixed member of the hinge, including its walls, ceiling and floor. The upper and lower compartments receive corresponding parts of the door jamb. The entire housing is affixed to said door jamb by means of screws inserted into apertures 27. The swinging member of the hinge is affixed to the door in much the same manner. The U shaped body accommodates a corresponding part of the door and screws fix it thereto through apertures 61.

The device is assembled as follows: The guide plate 11 is inserted into the middle compartment of the housing, its projectings 40 entering the apertures 37 in the rear wall 23 of said compartment. The hook-shaped arm is now inserted into said compartment, above said guide plate, the base portion 65 of the pintle entering slot 41, the stem portion 66 entering the shank portion 31 of one of the keyhole-shaped apertures, the head portion 67 entering the base portion 32 of said aperture and the guide member 70 entering slot 42. When the closed end of slot 41 is reached by the base portion of the pintle, said base portion drops into the particular circular aperture 33 which said slot 41 exposes. Then simultaneously, the check member 70 drops into the adjacent of the slots 34. The locking plate is now inserted into the same middle compartment, above said hook-shaped arm. One of the two slots 55 receives the stem portion 66. The projections 50 enter the notches 38 in the back wall 23, the projections 52 enter the base portions 32 of said keyhole-shaped apertures, and the projection 51 enters the depression 35. A screw 71 engages aperture 36 through aperture 54 and fixes the locking plate in place in the housing. The leaf spring 43 forces the two plates and the hook-shaped arm into pressure engagement with each other and with ceiling 22.

The hinge is now ready for use. To reverse the direction in which the movable member of the hinge is to swing, guiding plate 11 is turned upside down. The slot 42 is thereby caused to register with the other of the two slots 34 and the swinging member is ready to swing in the opposite direction. First, however, the swinging member must be turned upside down and the pintle and check member removed and similarly turned upside down in respect to the hook-shaped arm and re-inserted therein. At this point, it should be noted that the pintle and check member may be removably fixed in said hook-shaped arm, for this very purpose of reversing the swinging direction of the swinging member and with it, the door to which it is affixed. As a practical matter, however, once a hinge is set to swing in a certain direction, it is rarely removed to reverse that direction. Hence, the pintle and check member may be permanently fixed in the hook-shaped arm at the time of manufacture. The spring 43 may have to be affixed to the opposite side of the guide plate 11 when said plate is turned upside down as aforesaid.

When the check member 70 reaches the closed ends of slots 34 and 42 it checks further movement of the swinging member of the hinge in the direction toward said closed ends.

The device hereinabove described is but a preferred embodiment of the invention. Modifications, additions and subtractions may be incorporated therein without departing from the prin-

ciples thereof. Thus, although the device has been described throughout as being made of sheet metal, this need not necessarily be the case. It may be cast into shape. A resilient member such as a rubber cushion, or a tension member such as a steel spring might be introduced to cushion the impact between the check member 70 and the closed ends of slots 34 and 42. The guide plate 11 and the locking plate 12 may be omitted from the basic structure, if it be desired to reduce it to its barest essentials.

I claim:

1. A door hinge consisting of a fixed member and a swinging member, said fixed member comprising a housing including a pair of spaced horizontal plates forming a part thereof, a pair of spaced pintle seats formed in the upper of said plates registering with a pair of spaced pintle seats formed in the lower of said plates, a pair of arc-shaped guide slots formed in the lower plate, concentric, respectively, with the pintle seats in said plate, and a reversible guide plate and a locking plate inserted between said first mentioned plates, said swinging member comprising a housing, a hook-shaped arm extending outwardly therefrom, and invertible pintle and door check members affixed to said arm, said pintle being adapted to pivot in said pintle seats, said check member being adapted to slide in said slots, said guide plate having slots which guide said pintle and door check members respectively into said pintle seats and guide slots, said locking plate having slots which are closed at one end, the pintle being held at said closed end to prevent displacement thereof.

2. A door hinge consisting of a fixed member which is affixed to the door jamb and a swinging member which is affixed to the door, the fixed member comprising a box-like housing having a plurality of compartments which are open to the rear, and a compartment which is open to the front, the rearwardly open compartments being adapted to receive corresponding parts of the door jamb for affixing thereto, the forwardly open compartment being adapted to receive a reversible guide plate, a locking plate, and part of said swinging member, the floor of said compartment having a pair of spaced pintle seats and a pair of arc-shaped slots formed therein, concentric, respectively, with said pintle seats, the ceiling of said compartment having a pair of pintle seats formed therein in registration with the first mentioned pintle seats, the swinging member comprising a box-like housing having a single, rearwardly opening compartment, said compartment being adapted to receive a corresponding part of the door for affixing thereto, a hook-shaped arm extending outwardly from said housing and being adapted to enter the forwardly open compartment of the fixed member, and invertible pintle and door check members mounted in said arm, said pintle being adapted to pivot in said pintle seats, said check member being adapted to slide in said guide slots, said plate having slots

which guide said pintle and door check members respectively into said pintle seats and guide slots, said locking plate having slots which are closed at one end, the pintle being held at said closed end to prevent displacement thereof.

3. A door hinge consisting of a fixed member and a swinging member, said fixed member comprising a housing including a pair of spaced horizontal plates forming a part thereof, a pair of spaced pintle seats formed in the upper of said plates registering with a pair of spaced pintle seats formed in the lower of said plates, a pair of arc-shaped guide slots formed in the lower plate, concentric, respectively, with the pintle seats in said plate, a reversible guide plate having a pair of slots which expose either of said guide slots and the pintle seat with which the exposed slot is concentric, a locking plate having a pair of parallel slots which are open at one end and closed at the other end and register with the pintle seats, said locking plate being provided with means to affix it to the housing of the fixed member, said guide and locking plates being inserted between said first mentioned plates, said swinging member comprising a housing, a hook-shaped arm extending outwardly therefrom, and invertible pintle and door check members affixed to said arm, said pintle being adapted to pivot in said pintle seats, said check member being adapted to slide in said arc-shaped slots.

4. A door hinge consisting of a fixed member and a swinging member, the fixed member comprising a box-like housing having compartments which are open to the rear and a compartment which is open to the front, the rear compartments being adapted to receive corresponding parts of the door jamb for affixing thereto, the front compartment being adapted to receive a reversible guide plate, a locking plate, and part of said swinging member, the floor of said front compartment having a pair of spaced pintle seats and a pair of arc shaped slots concentric with said pintle seats, the ceiling of said compartment having a pair of pintle seats in registration with the first mentioned pintle seats, said guide plate having a pair of slots which expose either of said arc-shaped slots and the pintle seat with which the exposed slot is concentric, said locking plate having a pair of parallel slots which are open at one end and closed at the other end and register with the pintle seats, said locking plate being provided with means to affix it to the housing of the fixed member, the swinging member comprising a box-like housing having a single rearwardly open compartment, said compartment being adapted to receive a corresponding part of the door for affixing thereto, a hook-shaped arm extending outwardly from said housing and being adapted to enter the front compartment of the fixed member, and invertible pintle and door check members mounted in said arm, said pintle being adapted to pivot in said pintle seats, said check member being adapted to slide in said guide slots.

MICHAEL J. ECONOMIDES.
